UNITED STATES PATENT OFFICE.

EDGAR H. FREEMAN, OF TRENTON, NEW JERSEY.

LINING-FASTENING FOR ELECTRICAL LAMP-SOCKETS.

1,020,035.

Specification of Letters Patent. Patented Mar. 12, 1912.

Application filed July 22, 1909. Serial No. 508,895.

To all whom it may concern:

Be it known that I, EDGAR H. FREEMAN, a citizen of the United States, residing at Trenton, in the county of Mercer and State 5 of New Jersey, have invented certain new and useful Improvements in Lining-Fastenings for Electrical Lamp-Sockets, of which the following is a specification.

This invention relates to the subject of 10 casings for electrical lamp sockets, and has particularly in view an improved insulating-lining fastening for the cap of the socket or cap.

Heretofore various expedients have been 15 resorted to for the purpose of effectively securing in place what is known as the cap lining for lamp sockets, that is, a concavo-convex or dished washer or lining of insulating material which registers inside of 20 the removable cap part of a casing within which is housed the base and operating elements of a lamp socket. Most of these expedients have involved fastening projections or elements of various kinds formed in- 25 tegrally or otherwise with the sheet metal cap, or with the shell part of the casing, and coöperating with a lining which is sufficiently yieldable to be readily pressed over or snapped into engagement with such pro- 30 jections or elements. This particular method of fastening, that is, fastening elements or projections coöperating with a yieldable or springy insulating-lining is ob- 35 jectionable both from a structural and manufacturer's standpoint in depending 40 upon the resiliency of the material, and in the absence of positiveness in the lock or fastening itself.

It is for the purpose of obviating these 45 and other objections that the present invention is designed.

It will therefore be understood that a 50 special object of the present invention is to provide an improvement in cap lining fas- 55 tenings that responds more perfectly to the requirements of the National Board of Fire Underwriters Rules which require that a cap of electrical lamp sockets shall be lined with insulating material that is very thin 60 and which must be tough and tenacious, and which lining "must be so firmly secured to the shell that it will not fall out with ordinary handling of the socket." These 65 rules also require that the cap lining will provide a sufficiently smooth and well in-

sulated surface for the knot to bear upon, and that there must be sufficient room in the cap to enable the ordinary wiremen to easily and quickly make a knot in the cord and to push it into place in the cap without crowding. These various requirements are fully and satisfactorily met by the present invention, while at the same time the latter possesses a very great advantage from a manufacturer's standpoint in the particular of 65 entirely obviating careless and insecure positioning of sprung-in linings by the assemblers, which is a source of great annoyance both to the manufacturer and also to 70 the user of the socket.

With these and many other objects in view, which will more readily appear as the nature of the invention is better understood, the same consists in the novel construction, combination, and arrangement of parts hereinafter more fully described, illustrated, and 75 claimed.

A preferred embodiment of the invention is exemplified in the accompanying drawings, in which:

Figure 1 is an enlarged sectional view of the casing cap of the lamp socket illustrating an insulating-lining fastened in place according to the present invention. Fig. 2 is an enlarged cross sectional view thereof on 80 the line 2-2 of Fig. 1. Fig. 3 is an enlarged sectional view illustrating a method of rigidly holding or backing up the insulating-lining, while the locking spurs are 85 forcibly upset and driven into the outer surface of the lining.

Like references designate corresponding parts in the several figures of the drawings.

Referring to the embodiment of the invention shown in the drawings, the numeral 95 1 designates the cap part of a metallic casing or shell for an electrical lamp socket. This casing cap may be of any conventional form or design, but is usually made of sheet metal, and according to the requirements of the trade, and particularly of the fire underwriters associations, is designed to be lined upon its interior with a washer or lining 2 of insulating material. This washer or lining 2 is of a concavo-convex or dished type, 100 and of a size to register snugly within the correspondingly shaped cap.

Inasmuch as the present invention does not take into consideration the yielding or 105 springy character of the lining, it is to be 110

understood that the same may be made of any suitable insulating material available for the purpose.

According to the present invention, it is proposed to permanently fasten the lining 2 in place through the medium of a plurality of inwardly projecting integral pointed locking spurs 3 which are forcibly punched inwardly from the body material 10 of the casing, by exterior means, and driven directly into the body material of the lining 2, while the latter is rigidly held or backed up during the punching or upsetting operation. Various mechanical appliances may 15 be utilized for carrying out this particular process, but for purposes of illustration, there is shown in the drawings the principal elements of an apparatus for carrying this into effect. For instance, as shown in Fig. 20 3, the metal cap 1 with the lining 2 therein, are set over a rigid supporting anvil 4 and are held firmly on the latter through the medium of a suitable presser or foot 5 indicated by dotted lines in Fig. 3. With the 25 parts thus arranged and held, suitably operated punch points 6 are forced against and into the cap 1 from the exterior thereof with the result of offsetting inwardly the pointed locking spurs 3 and driving such spurs forcibly into the outer surface of the

lining 2, which lining, during such operation, is rigidly and immovably held by the supporting anvil 4.

From the foregoing it is thought that the construction and advantages of the herein 35 described invention will be readily apparent without further description.

I claim:

As an improvement in electrical lamp sockets, the combination of the socket casing 40 having a sheet metal cap, and a non-yielding thin lining of insulating material initially and permanently having a close registering fit within and solidly against the inner surface of the cap and presenting a smooth 45 and rigid insulating surface for the wiring to bear against, the said cap being provided in its metal wall with a series of spaced integral inwardly projecting prongs penetrating the fibrous rigid body of the lining and 50 permanently locking the same against movement or displacement in any direction after the locking-in operation.

In testimony whereof I hereunto affix my signature in the presence of two witnesses. 55

EDGAR H. FREEMAN.
